ABSTRACT OF THE DISCLOSURE

Weight of silkworm cocoons, and especially of cocoon layers, is increased by feeding the 4th instar silkworm larvae feedstuff containing a compound of the formula

wherein X is a member selected from the group consisting of O and S, and each of R₁, R₂ and R₃ is dialkylamino, or ethyleneimino (aziridin-1-yl).

This invention relates to a method for increasing the weight of silkworm cocoons, especially of cocoon layers, and to appurtenant feedstuff for silkworm larvae. More particularly, this invention relates to the method which comprises feeding the 4th instar silkworm larvae feedstuff containing a compound of the formula

(I)

wherein X is O or S, and each of R₁, R₂ and R₃ is dialkylamino or ethyleneimino (aziridin-1-yl), the alkyl having a maximum of four carbon atoms and the ethyleneimino being unsubstituted or substituted by alkyl having a maximum of four carbon atoms; and to the said feedstuff itself.

Although many improvements in mulberry leaves, artificial feedstuffs for silkworm larvae, race of silkworms and methods of rearing the larvae have been proposed for the purpose of increasing the weight of cocoons, none of these prior proposals has provided a satisfactory effect in increasing the cocoon weight.

One object of the present invention is to embody a satisfactory method for increasing the weight of silkworm cocoons, especially of cocoon layers. Another object of the present invention is to provide an artificial feedstuff for rearing silkworm larvae, especially in 4th instar larvae

These objects are achieved, and cocoons and cocoon layers of increased weight are obtained by the present invention, according to which the 4th instar silkworm larvae are reared on feedstuff containing compound (I) supra, while the weight of the cocoons rather decreases when any other instar silkworm larvae than the 4th instar are reared on the said feedstuff.

As compounds of Formula I, there may, for example, be used

Hexamethylphosphoryl amide:

2

Hexaethylphosphoryl amide:

Hexabutylphosphoryl amide:

Triethylenephosphoryl amide (also termed tris(aziridin-1-yl)phosphorine oxide):

Tris(2-methylaziridin-1-yl)phosphorine oxide:

Tris(2-ethylaziridin-1-yl)phosphorine oxide:

Triethylenethiophosphoryl amide:

As aforesaid, in the method of the present invention, an increase of weight of silkworm cocoons, especially of silkworm cocoon layers can be attained by feeding a feedstuff containing compound (I) to the 4th instar silkworm larvae. As feedstuff containing compound (I), there may be employed, for example, mulberry leaves incorporated with compound (I), or artificial feedstuff containing compound (I), together with conventional components of artificial feedstuff for silkworms.

Mulberry leaves incorporated with compound (I) may be prepared by, for example, spraying a solution of compound (I) onto fresh mulberry leaves, or immersing the leaves in the solution.

The quantity of compound (I) to be supplemented to the fresh mulberry leaves is practically about 0.005 to about 0.6% by weight relative to the fresh mulberry leaves.

The compound (I) may be supplemented to a conventional artificial feedstuff composed of e.g. terpenes (which may however be omitted), β -sitosterol with or without flavonoids, cellulose, powder, choline, nucleic acid or its derivatives, chlorogenic acid, etc., and sugar, inorganic phosphate, inorganic silicate, inositol, etc. As further per se conventional components of such feedstuff, which are helpful for the growth of silkworm larvae, there may, for example, be used agar-agar, sodium carboxymethylcellulose, methylcellulose, alginic acid; soybean powder, parched bean flour, defatted soybean powder, bean curd, dried fermented soybean powder, defatted and dried bean paste; cereal flour such as rice flour, barley flour, wheat flour, etc.; yeast products such as dry yeast, yeast extract, extracted fluid of yeast, extracted yeast cake; straw ashes;

and fish meal. These also serve as carrier. Further there may be included the following per se conventional nutritional components for the growth of silkworm larvae:

Animal or plant proteins;

Aminoacids such as glutamic acid, aspartic acid, leucine, lysine, tryptophane, valine, serine, proline, glycine, alanine, isoleucine, phenylalanine, arginine, methionine, threonine, or their salts;

Vitamins such as pantothenic acid, nicotinic acid, vitamin B₁, vitamin B₂, vitamin B₆, vitamin B₁₂, vitamin C,

by weight of tris(2 - methylaziridin - 1 - yl)phosphorine oxide, prepared by immersing fresh mulberry leaves in a 0.05% aqueous solution of tris(2-methylaziridin-1-yl) phosphorine oxide and drying the leaves.

Diet 3: mulberry leaves admixed with about 0.02% by weight of tris(2 - methylaziridin - 1 - yl)phosphorine oxide, prepared by immersing fresh mulberry leaves in a 0.1% aqueous solution of tris(2-methylaziridin-1-yl) phosphorine oxide and drying the leaves.

Results:

Diet	Number of silkworm larvae tested	♀		♂	
		Weight of a cocoon (average, milligrams)	Weight of a cocoon layer (average, milligrams)	Weight of a cocoon (average, milligrams)	Weight of a cocoon layer (average, milligrams)
1-----	400	2,560	554	1,930	508
2-----	400	3,050	660	2,220	574
3-----	400	3,010	647	2,240	589

vitamin D, biotin, folic acid, vitamin K, vitamin E, vitamin P, inositol, orotic acid, α -lipoic acid;

Inorganic salts such as calcium carbonate, sodium carbonate, sodium bicarbonate, sodium chloride;

Honey, beehive honey or honey products;

Pectin;

Enzymes such as diastase, papain, trypsin;

Preservatives such as sodium dehydroacetate, vitamin K₃, sodium sorbate;

Antibiotics such as streptomycin, oleandomycin, chloramphenicol;

Sulfa drugs such as sulfisomidine, sulfisoxazole; and

Glucuronic acid or its salts such as sodium salt, potassium salt, calcium salt, ammonium salt, organic amine salt, ethyl glucuronate, glucuronic acid amide, 2-amino-2-desoxy-D-glucuronic acid or its salts, N-glucuronosyl-glucosamine or its salts.

The quantity of compound (I) added to an artificial feedstuff may vary with conditions such as the kind or quantity of other components in the artificial feedstuff. Generally, it is preferable to employ about 0.005 to about 0.2% by weight of the compound relative to the total weight of the dried artificial feedstuff.

In the method of the present invention, silkworm larvae are reared in per se conventional manner except that they are fed the above-mentioned feedstuff at the 4th instar stage.

The following examples are of presently preferred illustrative embodiments of the invention. In these examples, "part(s) by weight" is referred to as "part(s)."

EXAMPLE 2

The 4th instar silkworm larvae (F₁ hybrid of Gunko x Banri) are reared for the first 2.5 days of the 4th instar on following per se conventional Diet 4 or the novel Diet 5, then the larvae are reared and mounted in conventional manner to allow them to spin cocoons. Weight of the resulting cocoons and of the cocoon layers is measured.

Diet 4:

	Parts
30 Dried mulberry leaves powder	11.0
Defatted soybean powder	34.0
Cellulose powder	23.0
Potato starch	23.0
Wesson's minerals ¹	0.5
Vitamin mixture ²	0.5
Glucose	5.4
Ascorbic acid	1.4
β -Sitosterol	1.2

40 ¹ Consisting of NaCl, KCl, KH₂PO₄, Ca₃(PO₄)₂, CaCO₃, FePO₄, MgSO₄, KAl₂(SO₄)₂·12H₂O, CuSO₄, MnSO₄ and KI in the weight ratio of

52.5 : 60.0 : 15.5 : 74.5 : 10.5 : 7.4 : 45.0 : 0.05 : 0.2 : 0.1 : 0.03

45 ² Consisting of vitamin B₁-HCl, vitamin B₂, vitamin B₆, nicotinic acid, calcium pantothenate, folic acid, biotin, vitamin B₁₂ and potato starch in the weight ratio of

10 : 10 : 10 : 20 : 20 : 2 : 2 : 10 : 3916

Diet 5: Diet 4 plus 3 milligrams of hexamethylphosphoryl amide per 10 grams of Diet 4.

Results:

Diet	Number of silkworm larvae tested	♀		♂	
		Weight of a cocoon (average, milligrams)	Weight of a cocoon layer (average, milligrams)	Weight of a cocoon (average, milligrams)	Weight of a cocoon layer (average, milligrams)
4-----	21	2,050	369	1,482	317
5-----	27	2,179	400	1,700	350

EXAMPLE 1

The 4th instar silkworm larvae (F₁ hybrid of Nichi 126 x Shi 126) are reared for the first 2.5 days of the 4th instar on the following Diet 1, Diet 2 or Diet 3, then the larvae are reared and mounted in conventional manner to allow them to spin cocoons. Weight of the resulting cocoons and of the cocoon layers is measured.

Diet 1: fresh mulberry leaves per se.

Diet 2: mulberry leaves admixed with about 0.01%

60 The 4th instar silkworm larvae (F₁ hybrid of Gunko x Banri) are reared for 5 days, i.e. through the 4th instar stage on Diet 4 described in Example 2 or Diet 6, then the larvae are reared and mounted in conventional manner to allow them to spin cocoons. Weight of the resulting cocoons and of the cocoon layers is measured.

65 Diet 6: Diet 4 plus 3 milligrams of triethylenethiophosphoryl amide per 10 grams of Diet 4.

Results:

Diet	Number of silkworm larvae tested	♀		♂	
		Weight of a cocoon (average, milligrams)	Weight of a cocoon layer (average, milligrams)	Weight of a cocoon (average, milligrams)	Weight of a cocoon layer (average, milligrams)
4-----	30	2,109	364	1,594	308
6-----	30	2,181	391	1,577	337

The results in the foregoing examples show that when the 4th instar silkworm larvae are reared on the feedstuff of the present invention, about 110-120% by weight of cocoons and cocoon layers relative to those obtained on the ordinary feedstuff are obtained. Essentially similar results are obtained in the same way when replacing hexamethylphosphoryl amide, tris(2-methylaziridin-1-yl)-phosphorine oxide and triethylenethiophosphoryl amide by any other compound of Formula I.

The artificial feedstuffs listed in the Examples are solely illustrative, and can be replaced by any other conventional artificial feedstuff for silkworm larvae.

Having thus disclosed the invention, what is claimed is:

1. A method for increasing the weight of silkworm cocoons, which comprises feeding the 4th instar silkworm larvae a feedstuff for said larvae selected from the group consisting of mulberry leaves and an artificial feedstuff, said leaves or artificial feedstuff containing a compound of the formula:

wherein X is a member selected from the group consisting of O and S, and each of R₁, R₂ and R₃ is a member selected from the group consisting of dialkylamino and

ethyleneimino, the alkyl having a maximum of four carbon atoms and the ethyleneimino being unsubstituted or substituted by alkyl having a maximum of four carbon atoms, wherein the amount of said compound relative to the weight of said leaves is approximately 0.005-0.6% by weight and the amount of said compound relative to the dried weight of said artificial feedstuff is approximately 0.005-0.2% by weight.

2. A method according to claim 1, wherein the compound is hexamethylphosphoryl amide.

3. A method according to claim 1, wherein the compound is tris(2-methylaziridin-1-yl)phosphorine oxide.

4. A method according to claim 1, wherein the compound is triethylenethiophosphoryl amide.
